attorney

UNITED STATES PATENT OFFICE

LUDWIG DENZER, OF HAMBURG, GERMANY

TYPE PAD FOR TYPEWRITERS

Application filed November 23, 1931, Serial No. 576,814, and in Germany March 14, 1931.

The type pads at present in use on typewriters are open to considerable objections consisting, amongst other things, in that special fixing means are necessary for fitting 5 the type pads on the metallic bow, whereas when employing type pads made of felt and the like sinking of the type levers into the pads cannot be avoided.

These objections are not only completely 10 overcome by the invention but a device is produced which avoids the otherwise troublesome vibrating of the type levers when striking and the jamming of the same connected therewith, and in which moreover a 15 dust catcher is provided which protects against the otherwise inevitable soiling of the type levers.

The type pad according to the invention is characterized substantially by a strip of 20 elastic material provided with a groove serving as dust catcher, said strip having a recess of trapezate cross-section, so that projections are produced which, forming a dove-tailed shaped groove, serve for clamping the 25 type pad on the known metallic typewriter bow. The type pad according to the invention is, with the exception of the groove-shaped part thereof, of wedge-shaped cross-section and has a plurality of parallel 30 grooves which are made, for example, in the shape of continuous longitudinal grooves. On the rear side of the type pad a plurality of dampers of any desired cross-section are provided, made of the same material as the 35 type pad itself or of different material.

An embodiment of the invention is illustrated by way of example in the accompanying drawing in which:

Fig. 1 shows the type pad in top plan view.

Fig. 2 is a section on line 2-2 of Fig. 1 showing the type pad fitted on a bow.

Fig. 3 is a cross section on the type pad on line 3-3 of Fig. 1.

The type pad consists of a strip made of 45 elastic material such as rubber, the upper portion *a* of said strip being wedge-shaped, whereas the surface directed towards the type levers has several juxtapositioned parallel 50 longitudinal grooves *b*.

On the rear side of the strip, where the type pad bears on the metallic bow *c*, several, for example two or three dampers *d* are cast in the middle portion designed to prevent the type levers from vibrating when they are struck. These dampers are of any desired cross-section. The wedge-shaped part *a* of the type pad merges into a groove *e*, which serves for collecting the dust coming from the ink rubber during erasing and consequently prevents the dust from dropping on to the key levers and the like. The strip of elastic material serving as type pad has on its rear side a recess *f* of trapezate cross-section, so that two continuous projections *g*, *h* are produced. The projections *g*, *h* are for example cast-on and serve for clamping the type pad on the metallic bow *c* provided on every typewriter, without the aid of special fixation means. The curved middle portion of the metal bow or type bar *c* engages with the recess *f* and is therefore partly enclosed by the projections *g* and *h*. The shape of the above mentioned projections *g*, *h* is chosen so that a dove-tail shaped groove is produced.

The projections *g*, *h* forming the dove-tail shaped groove may, instead of being continuous as shown, be provided only at the ends of the metal strip *a* so that the middle portion thereof lies freely on the metal bow *c*. In this manner a very convenient fitting and removal of the type pad according to the invention is attained.

I claim:

1. A type pad for typewriters, comprising a strip of elastic material having in its outer surface a groove for catching the dust and in its inner surface a recess of trapezate cross section leaving projections forming with said recess a dove-tailed shaped groove for clamping the pad on the bow of the typewriter.

2. A type pad as specified in claim 1, in which the strip of material is, with the exception of the groove shaped portion thereof, of wedge shaped cross-section and has a plurality of parallel continuous longitudinal grooves.

3. A type pad as specified in claim 1 in

which a damper is arranged on the rear side of the elastic strip.

4. A type pad as specified in claim 1 in which on the rear side of the elastic strip several dampers of any desired cross section and of the same material as the type pad are arranged.

5. A type pad as specified in claim 1 in which on the rear side of the elastic strip 10 several dampers of any desired cross section and of different material from that of the type pad are arranged.

In testimony wherof I affix my signature.
LUDWIG DENZER.
